(57) **CLAIM**

The ornamental design for a separator housing for a protective electrical wiring device, as shown and described.

DESCRIPTION

FIG. 1 is a bottom isometric view of a separator housing for a protective electrical wiring device in accordance with a first embodiment showing my new design;

FIG. 2 is a top isometric view thereof;

FIG. 3 is a bottom plan view thereof;

FIG. 4 is a top plan view thereof;

FIG. 5 is a first side elevation view thereof;

FIG. 6 is a second side elevation view thereof;

FIG. 7 is a third side elevation view thereof;

FIG. 8 is a fourth side elevation view thereof;

FIG. 9 is a bottom isometric view of a separator housing for a protective electrical wiring device in accordance with a second embodiment showing my new design;

FIG. 10 is a top isometric view thereof;

FIG. 11 is a bottom plan view thereof;

FIG. 12 is a top plan view thereof;

FIG. 13 is a first side elevation view thereof;

FIG. 14 is a second side elevation view thereof;

FIG. 15 is a third side elevation view thereof; and,

FIG. 16 is a fourth side elevation view thereof.
